US00D897995S

(12) **United States Design Patent** (10) **Patent No.:** **US D897,995 S**
(45) **Date of Patent:** **** Oct. 6, 2020**

(54) **HEADPHONE**

(71) Applicant: **Logitech Europe S.A.**, Lausanne (CH)

(72) Inventors: **Stephen Duddy**, Moama (AU); **Kuo-yu Kao**, Hsinchu (TW); **Jeremy Saxton**, Draper, UT (US); **Guillaume Mathias**, Park City, UT (US); **Shyh-Dean Chen**, Hsinchu (TW); **Jeffery Cheung**, To Kwa Wan (HK)

(73) Assignee: **LOGITECH EUROPE S.A.**, Lausanne (CH)

(**) Term: **15 Years**

(21) Appl. No.: **29/661,685**

(22) Filed: **Aug. 29, 2018**

(51) LOC (12) Cl. **14-01**

(52) U.S. Cl.

USPC **D14/223**

(57) **CLAIM**

The ornamental design for a headphone, as shown and described.

DESCRIPTION

FIG. 1 is a top, front, right-side perspective view of a headphone, showing our new design;

FIG. 2 is a top, back, left-side perspective view thereof;

FIG. 3 is a bottom, front, left-side perspective view thereof;

FIG. 4 is a bottom, back, right-side perspective view thereof;

FIG. 5 is a left-side view thereof;

FIG. 6 is a front view thereof;

FIG. 7 is a right-side view thereof;

FIG. 8 is a back view thereof;

FIG. 9 is a top view thereof; and,

FIG. 10 is a bottom view thereof.

The broken lines shown in the drawings depict portions of the headphone that form no part of the claimed design.
